UNITED STATES PATENT OFFICE

168,365

GARDENER'S GLOVE

Otto Merkel, Hawthorne, N. Y.

Application January 24, 1952, Serial No. 18,195

Term of patent 14 years

(Cl. D3—11)

To all whom it may concern:

Be it known that I, Otto Merkel, a citizen of the United States, residing at Hawthorne, county of Westchester, and State of New York, have invented a new, original, and ornamental Design for a Gardener's Glove, of which the following is a specification, reference being had to the accompanying drawing, forming part hereof.

In the drawing:

Fig. 1 is a rear view of a gardener's glove, showing my new design,

Fig. 2 is a front view thereof,

Fig. 3 is a side view,

Fig. 4 is a front view perspective view,

Fig. 5 is an enlarged detail view of one of the finger tips; and

Fig. 6 is a sectional view taken along the line 6—6 of Fig. 1.

I claim:

The ornamental design for a gardener's glove, substantially as shown and described.

OTTO MERKEL.
